SMOKING PIPE

Antonio La Marca Pirrone, New Kensington, Pa., assignor of three per cent to Alfred Dixon, three per cent to Thomas Dixon, three per cent to Robert Dixon, four per cent to Emil Sprumont, Sr., four per cent to Emil Sprumont, Jr., one per cent to Frank Mento, Jr., one per cent to Christy Mento, and one per cent to Tony Pollino, all of New Kensington, Pa.

Application February 8, 1933, Serial No. 655,813

1 Claim. (Cl. 131—22)

This invention relates to smoking pipes and has for the primary object, the provision of means for closing the tobacco chamber or bowl so that sparks from the burning tobacco may not escape and set fire to inflammable material in the vicinity thereof and said means also providing a novel appearance to the device as well as a support for the igniter whereby the tobacco within the bowl may be easily lighted and thus eliminate the use of matches and thereby reduce fire hazards.

With these and other objects in view this invention consists in certain novel features of constructions, combination and arrangement of parts to be hereinafter more fully described and claimed.

For a complete understanding of my invention, reference is to be had to the following description and accompanying drawings, in which

Figure 1 is a side elevation illustrating a smoking pipe constructed in accordance with my invention.

Figure 2 is a vertical sectional view illustrating the same.

Figure 3 is a plan view illustrating the housing or casing partly open so that the igniter may be adjusted or refilled with fuel.

Figure 4 is a view similar to Figure 3 showing the casing or housing completely opened and entirely exposing the tobacco chamber or bowl.

Figure 5 is a sectional view taken on the line 5—5 of Figure 2.

Figure 6 is a perspective view illustrating the device in an open position.

Figure 7 is a side elevation illustrating the tobacco bowl or chamber removed from the casing.

Figure 8 is a plan view illustrating the same.

Figure 9 is an end view illustrating a perforated closure for the tobacco chamber or bowl.

Referring in detail to the drawings, the numeral 1 indicates an outer casing or housing of substantially conical shape having located in its reduced end a bit attaching head or member 2 provided with a screw threaded bore 3 in which may be threaded the usual bit or mouth piece 4. A bowl supporting member 5 abuts the bit attaching member 2 and is provided with communicative and offset bores 6 and 7. A connecting tube 8 is threaded in the bore 6 and the bore 3 thereby detachably connecting the portions 5 and 2 with the smoke passage.

50 A semi-conical shaped bowl or chamber 9 is

located in the casing 1 with one end in abutting engagement with the member 5 and the bore 10 thereof communicates with the bore of a reduced screw threaded extension 11 threaded in the bore 7. A rib 12 is formed on the bowl or chamber and fits in a slot 13 of the casing 1. The enlarged end of the bowl or chamber 9 is spaced from the enlarged end of the casing and said casing between the enlarged end thereof and the enlarged end of the bowl or chamber is provided with a plurality of air openings 14. A perforated cover 15 is hinged to the enlarged end of the bowl or chamber to prevent the escape of burning tobacco therefrom into the casing and the enlarged end of the latter is closed by a hinged cover 16 further obviating the possibility of burning tobacco escaping from the device when in use.

The casing 1 is constructed of sections 17 and 18, the section 17 having the section 18 hinged thereto whereby the section 18 may form a cover which is preferably constructed of companion sections, as shown in Figures 1 and 3. One section of the cover carries a web 19 to support an igniter 20 within the casing. The igniter extends parallel with the bowl or chamber 9 with the wick end thereof located adjacent the mouth of the bore 10 of the bowl or chamber. The igniting wheel 21 of the igniter is located adjacent the wick and extends through a slot 22 in the casing whereby the igniter may be operated from the exterior of the casing without opening the latter. The filling and adjusting means of the igniter are located under the other section of the cover, as shown in Figure 3.

In use, tobacco may be readily placed in the bowl or chamber 9 by opening the covers 16 and 15 and after the filling of the bowl or chamber with tobacco, the latter may be ignited through the manipulation of the igniter 20 or the rotation of the igniting wheel 21 thereof. To allow the flame of the igniter to contact with the tobacco of the bowl or chamber, one wall thereof is perforated, as shown at 23. After the igniting of the tobacco the cover 16 may be closed, it being understood that the cover 15 having already been closed after the placing of the tobacco in the bowl or chamber and with the pipe smoked in this manner sparks are prevented from escaping from the device, whereby the device may be used with safety in the vicinity of inflammable material.

While I have shown and described the preferred embodiment of my invention, it will be understood that minor changes in construction, combination and arrangement of parts may be made without departing from the spirit and scope of my invention, as claimed.

Having described the invention, I claim:

A smoking pipe comprising a casing having a hinged section and an open end, a hinged cover

for closing said end of the casing, a mounting in said casing and having a bore, a mouth piece connected to said bore, a tobacco chamber carried by the mounting and in communication with the bore, a perforated hinged cover for closing the chamber, and said casing having perforations adjacent the perforated cover.

ANTONIO LA MARCA PIRRONE.
